UNITED STATES PATENT OFFICE.

CHARLES E. EMERY, OF BROOKLYN, NEW YORK.

IMPROVEMENT IN STEAM-ENGINES.

Specification forming part of Letters Patent No. **70,707**, dated November 12, 1867.

To all whom it may concern:

Be it known that I, CHARLES E. EMERY, of Brooklyn, in the county of Kings and State of New York, have discovered and invented certain new and useful Improvements in Steam-Engines; and I do hereby declare that the following is a full, clear, and exact description thereof, reference being had to the accompanying drawings, making part of this specification.

It is a patent fact that the best steam-engines utilize only one-tenth to one-ninth of the heat in the steam used. Scientific men speak of the loss as unexplained, and state that the steam-engine is yet in its infancy, and that no considerable improvement has been made in it since the days of Watts. In spite of all the efforts of inventors to economize fuel, the fact still stares them in the face that nearly ninety per cent. of the steam is wasted.

Many experiments have been made with superheated steam, and that principle may undoubtedly be carried with economy as far as mechanical means will allow. Most attention, however, has probably been paid to the enormous profits promised by theory from the expansion of steam; but it is well known that the expected gains from this source have never been practically realized.

Compared with full-stroke, the theoretical gain by cutting off steam at half-stroke is sixty-nine per cent. At quarter-stroke it is one hundred and thirty-eight per cent., and increases with the grade of expansion. Notwithstanding this, it is doubtful if a gain of fifty per cent. has ever been obtained in practice, which could all be attributed to expansion alone, rather than to differences in pressure, superheating, or some circumstance, often used in connection with expansion, and for which that principle has the credit, but which, in fact, increases proportionably the economy of the power nearly as much at one grade of expansion as another. Though many will deny this, the small percentage of the theoretical performance utilized in the best steam-engines, using expansion in the most approved manner, shows that there is a discrepancy somewhere. Still it is to the expansion of steam that we should look for further economy.

A steam-engine is simply a heat-engine. Water takes up the heat; steam is the result.

If steam be expanded, work is done. A quantity of heat the mechanical equivalent of the work done disappears, and leaves its vehicle—the water—in its original condition. In other words, steam is condensed. Theoretically, we should be able to carry on the expansion till the heat force is all utilized and the steam all becomes water. Practically, the steam-pressure can never be economically reduced below that necessary to equilibrate the resistances incident to the engine itself. Up to this point, then, we should expect gain; still we do not in practice realize it.

Modern discoveries in science have pointed out no reason why this is so. They only show that the pressure must reduce faster than the ordinates of a hyperbolic curve, on account of condensation due to work done and varying temperature. Then, since the theory of expansion is so conclusive, and we are not able to obtain results in accordance therewith, should we not look carefully at the practical side of the question, and strive to find, in the materials used, or in their form, disposition, or movements, some fault to which may be attributed the losses? First, we must allow that a steam-engine cylinder appears to hold the steam, and that the operation of the valve-gear and piston and its connections undoubtedly permits its expansion, and transmits the force derived therefrom to the desired point. I say the cylinder appears to hold the steam. Now, what is steam? We may say water which, by the action of heat, has had work done upon its particles, separating and agitating them. Less literally, it is simply water and heat. Does the cylinder hold both? Put your hand on it and see. Ah! your flesh is not wet, but is burned—that is, the cylinder holds water, but not heat. It is, in fact, ready, at the first opportunity, to give away the very force we wish to utilize. Your hand robbed the cylinder of a little heat, the cylinder robbed the inclosed steam, leaving a little useless water. However, we expect loss from the outside, and guard against it by covering of felt or similar material.

Let us inquire if any similar loss can take place on the inside. There is nothing but steam there, you say. Why was your hand burned? Simply because it was colder than the metal. Is the steam ever cooler than the

metal? Certainly it is, at the very time it is going out of the cylinder, and can carry all the heat it receives away to waste.

The differences in temperature inside a steam-cylinder during a double stroke of the piston are very considerable. The steam enters usually at near the boiler pressure and temperature, and if it be expanded the temperature necessarily falls from the time the cut-off valve closes to the end of the stroke. When the exhaust-valve opens, the temperature again falls to that due to the back pressure. For example, if steam, admitted to the cylinder at a pressure of thirty-five pounds per square inch above the atmosphere, be cut off at a quarter of the stroke from the beginning, and at the end exhausted into a condenser against a back pressure of two pounds, its temperature during the first quarter of the stroke will, in round numbers, be 280° Fahrneheit, and gradually fall to 205° at the end of the stroke, when, after the exhaust, it will be suddenly reduced to 130° , remaining so during whole return-stroke. The metal of the cylinder at first necessarily becomes nearly as hot as the boiler-steam; but when the communication with the boiler is shut off the temperature of the confined steam at the end of the stroke becomes 75° lower than that of the metal, and the difference increases to 150° when the exhaust takes place, and remains so during the entire return-stroke.

Tyndall has shown that aqueous vapor is a very powerful absorbent of radiant heat. When, then, as we have shown, the temperature of the metal of a steam-cylinder is so much higher than that of the inclosed steam, a great deal of heat must be radiated from the metal, absorbed by the steam, and carried with it out of the cylinder. The heat radiated from the metal must be resupplied from the incoming boiler-steam to adjust the temperatures.

When the boiler furnishes saturated steam, since that is its maximum density, as steam, at the point of saturation, no heat can be taken from it without producing condensation. Hence the heat required to reheat the cylinder and that transmuted into work both produce condensation. A portion of the steam yields up its latent heat and collapses from the volume of steam to that of water at the same temperature. So long as the steam-valve is open new steam enters to keep up the pressure. Hence it often occurs, in practice, that twice as much steam is used as is required by calculation. There is nothing strange in this if the metal of the cylinder, at the beginning of each stroke, is cool enough to condense about half the steam that enters. With superheated steam the effect is similar, though no condensation need take place. The free superheated goes to supply that necessary to reheat the cylinder and perform the work. This decreases the volume, and while the steam-valve is open more steam flows in to keep up the pressure. The density is thereby increased, and, like saturated steam, it re-

quires a larger quantity of boiler-steam to maintain the initial pressure and temperature.

Let us now carefully follow the steam through the cylinder of an engine, explaining the changes which take place upon the principles above stated. The metal of the cylinder being somewhat cooled during a previous stroke, in manner pointed out, sufficient steam enters not only to fill the space, but to reheat the metal and keep up the initial pressure. The steam is shut off, expansion takes place, and soon the temperature of the steam becomes lower than that of the cylinder. The metal, in turn, becomes the heater. It re-evaporates whatever water is in contact with it, and radiates its heat into the steam, and thus superheats it, or re-evaporates the suspended watery particles of condensation, as the case may be. All the heat taken from the metal during the steam-stroke is utilized, for it increases the volume or pressure of the steam, and thereby produces a dynamic effect on the piston. When the exhaust takes place, however, all the heat required to re-evaporate the water on the surfaces, all that can be radiated from the metal and absorbed by the steam, and that received by the steam by direct attrition against the heated sides of the cylinder and narrow ports during the time of the whole return-stroke, is carried away out of the cylinder, and, for the purpose of work, entirely wasted. All this heat has to be supplied at every stroke, to be again and again wasted and resupplied. The lost heat is furnished by an additional quantity of steam, which unfortunately enters and leaves the cylinder without showing its presence by an increase of pressure, wherefore calculations to determine the quantity of steam used are necessarily incorrect when founded, as is usual, upon the terminal pressures shown by indicator-diagrams.

In the famous Erie expansive experiments it was found that at the higher grades of expansion from forty to forty-five per cent. more steam entered the cylinder than was accounted for by calculation from the terminal pressure. About eight per cent. of this was condensed to furnish heat for the work; the rest was absolutely wasted. Boune mentions that in one of the noted double-cylinder pumping-engines in England thirty-three per cent. of the steam was unaccounted for by the indicator. In small engines the discrepancy often amounts to two-thirds of the steam used.

It would seem to be impossible for an engine to work when so much of the steam is condensed in the cylinder. Now, Tyndall has shown that a good absorbent is necessarily also a good radiator. So, when steam enters a cooled cylinder, though some water may be condensed on the surfaces, like dew, the whole body of the steam is also chilled by radiation, and the condensed water left suspended in the steam in a fog or cloud. A small quantity of water may possibly be held invisibly suspended, like the aqueous vapor in the atmos-

phere; but larger amounts undoubtedly form a cloud, from which, when the abstraction of heat is carried sufficiently far, water probably drops like rain.

The quantity of steam necessary to reheat the cylinder should increase slightly with the grade of expansion, for the metal is exposed to a temperature lower than its own for a larger portion of each stroke. But since less steam enters the cylinder at the higher grades, not only the quantity required for reheating, but also that condensed for the work, must form a larger proportion of the whole quantity. In other words, the percentage of water condensed and unaccounted for by the indicator must increase with the grade of expansion, at least up to a point where the metal is heated and cooled all that is possible in the time of a double stroke.

In accordance with the principles above adopted to explain the losses in steam-engine, we may account for the gains which are obtained by some forms of construction, and reconcile many statements which appear contradictory.

First, then, it is well known that large engines are more economical than small ones, even when using steam with the same degree of expansion. We can understand this from the fact that as the cylinder is enlarged the ratio of radiating-surface to capacity is proportionably diminished, and the metal also is farther removed from the main body of the steam.

Again, the Cornish engine is often referred to as a model of economy, and an example of the efficiency of extreme expansion. Others adopt the same pressure of steam and the same grade of expansion, but do not realize the same degree of economy. Why is this? Now, Cornish boilers are very economical; but that will not account for all the gain. On the principle above stated, we find, first, that Cornish engines are generally large, and for that reason economical. But more than this, they are single-acting. The hot boiler-steam never touches the coolest portions of the cylinder. It enters only at the top, and presses down the piston until the beam and heavy pump-rods are put in motion. The steam is then shut off, and the stroke completed by expansion. As the steam lowers in temperature the surrounding metal is correspondingly cooled. The return-stroke is accomplished by the weight of the pump-rods, and the piston simply displaces the steam from one end of the cylinder to the other through the equilibrium-valve. The upper or hot end of the cylinder is never in connection with the condenser, and the cool end is at no time in direct communication with the boiler. Is it strange that greater economy can be attained, using such an instrument as this, rather than a double-acting cylinder, each end of which must be heated and cooled at every stroke?

Again, the double-cylinder engine is considered very economical, and properly so, for the small cylinder is never in communication with

the condenser. The heat radiated from it is utilized on the large piston, which stands like a screen to prevent its going entirely to waste. Viewing the matter in this light, it is probable that the economy of the present double-cylinder engine could be increased by making less difference in the size of the cylinders than is usual.

Great differences of opinion exist as to what is the most economical point of cut-off in the ordinary double-acting engine. There is an undoubted gain within reasonable limits when the higher grades of expansion have the benefit of higher pressure steam than the lower grades, which is the only practical way of testing the matter when doing the same work in the same engine and with the same piston speed. But moderate expansionists say that they are entitled to as high a pressure of steam as is used in any case, and that they can thereby employ a smaller engine with no greater loss than is compensated for by diminished first cost and increased simplicity and reliability. The point about steam-pressure is well taken; but they forget that when doing the same work with the same pressure of steam increased expansion not only necessitates a larger engine, but brings the economy due, as above explained, to a larger engine *per se*. It is believed, therefore, that the views of the non-expansionists are not upheld by facts. There is, however, a limit to the application of the principle of expansion in engines as at present constructed, the best, as has already been said, utilizing only one-tenth of the heat.

I have above stated my theory fully, and have given some examples of its practical application. Still, many may doubt that a cause apparently so small can produce such large and injurious effects. I would, however, call attention to the fact that Tyndall, when experimenting with the very things that we have been discussing—viz., the vapor of water and radiant heat—made discoveries still more incredible. He found that the invisible aqueous vapor present at all times in the atmosphere had seventy times the absorptive effect on radiant heat of dry air. Any person who will carefully read his remarks on this subject, in connection with a careful study of the changes of temperature that occur in a steam-cylinder, which in fact confines a kind of aqueous vapor within radiating-surfaces, will, I think, agree with me as to the nature of the losses which are found in practice.

To prevent these losses, I long ago proposed to make the interior surfaces of a steam-cylinder of a poor conductor or poor radiator of heat; but I found that Tyndall had shown that a poor radiator—a polished surface, for instance—becomes a good one when a good radiating vapor like that of water is in contact with it. However, by making the interior surfaces of a poor conductor of heat, no more heat can be radiated or conducted away than is conducted to the surface. Therefore so much cannot be lost, and less steam will be re-

quired to reheat the surface. By using a poor conductor, with low specific heat, the benefit should be still more marked. After carefully considering the subject, my convictions were so strengthened by the considerations hereinbefore expressed, and by mathematical calculations, that I tried the matter practically. After some preliminary, though encouraging, experiments with incomplete apparatus, I constructed two cylinders of like dimensions, one of glass, the other of iron, in such a manner that either could be attached to a valve which regularly admitted steam from a boiler to the cylinder, and permitted its exhaust into a condensing-coil lying in a tub of water. The capacity of the two cylinders was made exactly the same, as was shown by transferring water from one to the other. When put, in turn, in the condition of a steam-engine cylinder, the iron cylinder used twice as much steam as the glass one, shown by the fact that twice the quantity of water came through the condensing-coil for the same number of movements of the valve. Steam of the same pressure was used in both cylinders, and the experiments were many times repeated, with substantially the same results. This settled the question. The glass cylinder in that case saved half the steam. With more expansion I expect still greater gains. A large proportion of the theoretical saving promised by extreme expansion may perhaps be realized. Whether my theories be right or wrong, I have at least demonstrated the practical value of non-conducting material for the interior surfaces of steam-cylinders.

Popularly speaking, in relation to heat, all materials are divided into two classes—"conductors" and "non-conductors." The metals constitute the first class, but differ among themselves in conducting-power. Thus copper and compounds in which it enters largely, such as brass, conduct heat less freely than silver, but better than iron. Other metals conduct heat less freely than iron. For instance, lead and German silver have only from three-fourths to one-half its conducting-power, and bismuth has but about one-sixth. Substances such as glass, porcelain, fire-brick, marble, and stones are known as "non-conductors," and many of them have but about one-thirtieth the conducting-power of iron. Cast-iron is almost universally employed in the construction of steam-cylinders, and it has lower conducting-power than brass or any other substance now practically used for the purpose.

The object of my invention is to produce economy in the steam-engine. I accomplish this by, and my invention consists in, lining or coating the interior surface of the cylinders of steam-engines with glass, porcelain, enamel, or equivalent material. I also propose to construct the whole cylinder of a poor conductor, and have made changes in the form of steam-engine cylinders and pistons, whereby certain portions of the surfaces that cannot always be

conveniently lined may be protected from direct radiation.

For the purposes of my invention one material used, as above expressed, is the equivalent of another when it conducts heat less freely than cast-iron; and the application of the words "poor conductor of heat" and similar expressions, as herein used, is limited to such materials as conduct heat less freely than cast-iron.

In the drawings, Figure 1 is a longitudinal section of an ordinary steam-engine cylinder, and shows a poor conducting-lining applied to the whole interior except the wearing-surfaces. Fig. 2 is a transverse section of the same. Fig. 3 is a longitudinal section of the same cylinder altered so that the steam is displaced from the wearing-surfaces into the protected ends by blocks on the piston. Fig. 4 is a transverse section of the same. Fig. 5 is a longitudinal section of a steam-cylinder containing a long plunger-piston, more particularly described hereinafter. Fig. 6 is a transverse section of the same. Fig. 7 is an end view, Fig. 8 is a horizontal section, and Fig. 9 is a side view, of a steam-cylinder of the ordinary form, with all the interior surfaces lined, and some peculiarities of construction, hereinafter described. Fig. 10 is a vertical cross-section, and Fig. 11 is a vertical transverse section, of another cylinder, hereinafter described. Figs. 12 and 13 are similar views of a poor conducting-cylinder hooped with strengthening material.

The same letters in all the figures refer to corresponding parts.

A represents the piston; a, the piston-rod; B B', the cylinder-heads; C C, the cylinder-ports; D, the slide-valve; E E, the slide-valve faces; and x x, the protecting material or lining, made of a poor conductor of heat. The sections of the metal of the cylinders are represented by the Prussian-blue tint. There are very many materials which conduct heat slowly that can be applied as a protecting-lining to steam-engine cylinders; but all of them cannot be used for the surface upon which the piston rubs. Figs. 1 and 2 are intended to show what proportion of the radiating-surfaces to which steam is exposed in an ordinary steam-cylinder may be covered by a material not adapted for a rubbing-surface.

By reference to the drawings, it will be seen that the lining or protecting material x x covers the whole interior surface of the steam-ports C C from the base of the cylinder to or nearly to the valve-faces. It is placed on the inside of both cylinder-heads B and B', on both sides of the piston A, and lines the clearance-space, which extends from the heads of f and g, where the wearing-surface of the cylinder commences. In a puppet-valve engine the interior of the nozzles and the disks of the valve would be covered. On this plan a large part of the metal surfaces is left unprotected; but the exposed wearing-surface from f to g

forms a less proportion of the whole surface in cylinders of the same capacity, the larger the diameter and shorter the stroke.

Figs. 3, 4, 5, and 6 represent plans by which direct radiation is prevented from the metal wearing-surfaces into the main body of the steam, and a poor conducting material, not adapted for a bearing-surface, may be used for linings.

In Figs. 3 and 4 the piston is lengthened by the addition of blocks J and K, and the cylinder by extensions G G. The blocks displace the main body of the steam from opposite the wearing-surfaces into the ends G G, which are lined, as shown. Steam is admitted by making the ports C C in the ends G G, or by cutting off one side of the blocks. J and K are shown at F F. A plan of protecting the piston is also shown in Fig. 3, more useful for trunks with large surfaces than for ordinary piston-rods. A pipe, b, section in red, of about the length of the stroke, surrounds the rod a, and is secured at one end to the inside of head B. The block J has a hole in it, which works over the pipe when the piston moves in that direction. The pipe b is made either of poor conducting material, or is covered with such, at least on the outside, and therefore cuts off radiation to and from the rod and the main body of the surrounding steam. The surfaces of rod and hole in J may be protected also, if desired. The pipe b may also be secured to the piston, and run into an annular space between the rod and a hole in cover B.

In Figs. 5 and 6 the piston A is, in fact, a plunger, something more than the length of the stroke, turned on the outside, and made to slide in, and be kept tight by, packing-rings c c, surrounding the piston, and placed in the middle of the length of the cylinder. The cylinder, except at the packing-space, is of the usual shape, of sufficient length to allow the piston to make its stroke, and furnished with usual ports C C. Besides the rings, the piston has a short bearing on either side of them between f and g, and the remainder of the length is counterbored or made larger, and receives the protecting material x x, as shown, the heads, ports, &c., being protected as before; and the piston-rod may be, if desired, on the plan shown in Fig. 3. This cylinder is made in two parts, bolted together at the center. One has a space, in which are the packing-rings c c and springs d d, which press the rings against the piston. A follower, i, holds in the rings, and makes a flush joint with the cylinder-flange to meet that on the other part, in manner shown. To prevent dividing the cylinder, the rings may be sprung in before the piston is put in place, or may be put in in segments, hand-holes, or other openings being provided for this purpose, or to "set out" the springs, or examine the packing, as the case may be. Steam may also be readily admitted behind the rings to keep them tight, and may have a constant pressure derived from the boiler, or a vary-

ing one from the cylinder, as is usual. In this cylinder just described the main body of the steam in the space O, for instance, is neither in contact with nor exposed to radiation from any good conducting-surface. All sides are protected. Very small quantities of steam will leak in beside the piston A, and receive heat by conduction; but such will quickly become superheated to the temperature of the metal, and stop doing mischief. It is evident that the cylinders, with elongated pistons, (represented in Figs. 3, 4, 5, and 6,) may, if desired, be made entirely of the poor conducting or protecting material x x.

In Figs. 7, 8, and 9 the cylinder and piston are represented of the usual form; but all the interior surfaces of the cylinder are lined, and the piston-packing rubs on the non-conducting covering.

By the "interior surfaces of the cylinder" I mean the surfaces with which the steam comes in contact while in the cylinder. The expression, therefore, is intended to include not only the interior surfaces of the cylinder proper, but also those of the cylinder-passages, cylinder-heads, and the exposed surfaces of the piston, which, in one sense, forms one side of the cylinder.

It is desirable in all cases to exclude the condense-water from the cylinder at every exhaust. This is sometimes done in horizontal engines by making the exhaust-port in the bottom of the cylinder; or, when the cylinder-ports answer for both steam and exhaust, they are often put in the side, with the bottom of the port level with the bottom of the cylinder.

In Figs. 7 and 9 the ports C C incline from the bottom of the cylinder to the valve-face E. By this means the water will be carried out of the cylinder by gravity and the force of the exhausting steam.

When the ports C C make the usual double turn shown in Fig. 8, it is difficult to line them. To obviate this, I have made the valve-face and part of the ports in a separate plate, M, which meets the cylinder-casting, with a steam-tight joint on the line m. The plate is bolted fast to the cylinder through suitable flanges, and the steam-chest bolts to the plate in the usual manner.

It is proposed to make the cylinder, and, if desired, the cylinder-heads, piston, and piston-rod, of a homogeneous material of low conducting-power. Glass cylinders of moderate size may be made in this way. Large cylinders, however, of glass, porcelain, or other brittle substances, will need strengthening. Figs. 10, 11, 12, and 13 represent plans for doing this, X being the cylinder, of low conducting-power.

In Figs. 10 and 11, X is surrounded by a strong cylinder, N, of larger diameter, an annular space, n, being left between the two. The heads should be of poor conducting material, or lined with it. The ports may be made in the heads, as shown, if desired.

It is proposed to fill the annular space n either with cement or an elastic substance,

like india-rubber or hemp, compressed sufficiently to prevent the inner cylinder from bursting. The space *n* may also be filled with steam, and serve, in some measure, as a steam-jacket, and at the same time resist fracture by a pressure opposite to that of the cylinders. Again, the space *n* may be formed into one or more chambers, and filled with a fluid—oil, for instance—and this may receive steam-pressure from any source desired.

By having a series of chambers, as shown in the dotted lines, with small pipes *p p p* running through the fluid into them from the cylinder, the varying pressures inside the non-conducting cylinder will be transmitted to the outside, and there will be little danger of fracture from simple pressure. Of course, steam direct from the cylinder may be admitted into this chambered jacket; but the outer cylinder in that case had better be lined.

In Figs. 12 and 13 the poor conducting cylinder *X* is hooped with strengthening material. The hoops *N N* may be placed directly on the cylinder, or have elastic material *n* interposed.

It will be observed that a hooped cylinder is simply the mechanical equivalent of the combination shown in all the figures from 1 to 9, for, considering the lining *x* as the cylinder proper, the surrounding metal serves like a hoop to strengthen it.

The following is a list of the principal materials which I propose to use for the interior surface of steam or gas engine cylinders, viz: glass, porcelain, and all kinds of pottery-ware, and the glazing usually applied thereto, enamel, fire clay or brick, alum, mica, asbestos, carbonate and sulphate of lime, charcoal and plumbago, bismuth, antimony, lead, German silver, and a compound metal hereinafter mentioned; also, in some cases, wood and vulcanized india-rubber. All of these substances conduct heat less freely than cast-iron, and for that reason they and other materials, the equivalents thereof in that respect, may be economically used for the purposes specified.

Glass possesses many qualities which render it specially applicable. It has very low conducting-power, the best kinds are little acted on by steam, and its hardness renders it fit for a wearing-surface. It is liable to crack when the temperature is changed suddenly; but when well annealed small cylinders may be made of it, and used without strengthening. It may be employed with advantage for an interior cylinder on one of the plans shown in Figs. 10 to 13. It may also be made in staves or plates, and fitted as a lining to cylinders.

Porcelain, stone, or pottery-ware, fire clay or brick, and plumbago or crucible material may be used substantially in the same manner as glass. The glazing put upon most of these substances may be applied to all, and will answer for the wearing-surface.

I have constructed a metal cylinder, the interior surfaces of which are coated with enam-

el, and it is proposed to make entire cylinders of the same material.

Enamel has many properties common to both glass and porcelain, and is used to line cooking-vessels, stationary wash-basins, &c. The ingredients of many kinds of enamel may be found in receipt-books, though the business is usually conducted secretly. One kind is composed of about sixteen parts of red lead mixed with sixteen parts of powdered flint glass and about three parts of calcined borax. Porcelain-clay is sometimes an ingredient. The materials are thoroughly incorporated by melting. The compound formed is poured into water, and afterward ground to powder.

The enamel is applied substantially as follows: The metal is first cleaned, and the ground enamel is made into a paste with spirits of turpentine or other liquid, and applied to the surfaces. It is then dried, and the whole casting is heated sufficiently to melt the glazing. The cylinder represented in Figs. 7 to 9 may be easily operated on in this manner, for by removing plate *M* all parts of the ports become accessible.

The castings are sometimes changed in shape by the severe heat required to melt the enamel; but if the plan of construction shown in Figs. 3 to 6 be used this will make little difference.

When the piston rubs on the enamel, as in Figs. 7 to 9, the cylinder may be bored before the process, and the rubbing-surfaces afterward ground, so as to be accurate.

A cylinder may be cut directly out of marble or other stone. The scale, which, by its poor conducting property, so injures the evaporative efficiency of steam-boilers, may be applied with advantage to the cylinders by simply heating water in them, which holds in solution sulphate of lime and other salts. Plaster-of-paris may be cast in plates for linings, or directly on the interior surfaces of the cylinder. Either marble, chalk, alum, mica, asbestos, or charcoal, in a powdered state, may be mixed with plaster and operated with in the same manner, or be pressed in a mold into the proper shape; or one or more of the same may be made into a cement with linseed-oil or equivalent substance, and put in shape for linings.

The simple metals above mentioned may be used, so far as is practicable, for both cylinders and linings. German silver may be employed in a similar manner, and may be sufficiently hardened with antimony to answer for a wearing-surface. I propose to use an alloy or compound metal for both cylinders and linings, composed of seven parts of lead and one of antimony, the hardness being varied by slightly changing the proportion of antimony. A portion of the antimony may be replaced by bismuth, which will decrease the conducting-power, and not alter the mechanical properties of the compound materially. Though all metals are good conductors compared with glass or other silicate, it may be necessary, in

some cases, to use a metallic substance for the wearing-surface, and protect the other interior surfaces with different materials. Wood may be employed for either cylinders or linings, but should be well soaked in oil or similar substance to close its pores. Sheets of india-rubber may be employed as linings where little oil is used in the cylinder.

I have found that felt cloth inside a steam-cylinder absorbs water, which must be heated and cooled at every stroke. Cloth, fur, and porous material, I conclude, can only be used with advantage when the steam is sufficiently superheated to prevent a deposition of water.

When the linings are made in sheets or plates they may be secured by screws passing through them, or by wedges, or in an evident manner, and metal plates may be hammered so as to hold themselves in place, like the staves in an air-pump of a sea-going steamer.

The transmission of heat is retarded by a break in the conductor. It is proposed, therefore, to line some of the surfaces of a steam-cylinder with a sheet of metal so thin that it will hold little heat of its own, and the break in the continuity of the conductor will retard heat passing to and from the surrounding metal, and thus prevent great losses. Such a lining could be set out from the cylinder a little by studs, and thus prevent conduction entirely, and the thin metal would act as a screen to intercept radiant heat. I would not, however, use the space between the lining and cylinder as a steam-jacket, for that would defeat the very object I have in view, as the metal would thereby be kept hot, not only during the steam but during the exhaust stroke, when the heat conducted through it would be carried to waste. I propose to fill the place behind the metal screen either with poor conducting material, which the sheet metal holds in place, or I would let the steam in the cylinder circulate on both sides of the screen, when that next the metal would be superheated and cause injury to that extent; but the main body of the steam would be protected.

I believe that greater economy can be obtained, even in a non-conducting cylinder, with superheated rather than saturated steam, as the superheat will prevent water from lying on the metal surfaces to be heated and cooled at each stroke. I have found that a film of water adheres to the interior surface even of a glass cylinder when saturated steam is used. Single-acting and double-cylinder engines should be slightly more economical than the ordinary double-acting engine, even when all the cylinders are protected.

It is anticipated that in some instances it may be impracticable to make the whole interior surfaces of the cylinder of a poor conductor of heat. Nor is this necessary in order to attain economy. The losses occasioned by

unprotected surfaces will simply be in some measure proportioned to their extent, and the total gain be less than when the whole interior is protected. It is not proposed either to make all parts of the interior surfaces in the same way or of the same material. For instance, the cylinder proper may be made entirely of a poor conductor, and the heads be lined with such, or vice versa.

It is evident that a poor conducting cylinder will be useful in all engines operated by gases or liquids, which change in temperature while passing through the cylinder.

The principal feature of my invention is the practical discovery that it is economical to construct steam-engine cylinders of a poor conductor of heat. Watt, in his early experiments, tried a wood cylinder, so that it might not be cooled by the condensing water, which was then admitted into the cylinder; but he still had the water which remained to heat and cool at every stroke, and abandoned the experiment. By condensing the steam in a separate vessel, he made the great improvement in the steam-engine which immortalized his name. Still, we can now see that he stopped half-way.

Again, glass steam-cylinders are in daily use for toy engines, glass being employed merely because it is transparent. Its real value for steam-engine cylinders is unknown, and therefore of no use to the world.

I disclaim glass steam-engine cylinders when simply used because transparent, for instruction and amusement rather than the attainment of a new effect in the economical performance of the useful work for which steam-engines are generally employed. I have, however, made the new and useful discovery that there is economy in constructing the interior surfaces of a steam-cylinder of a material which conducts heat less freely than that commonly employed, and have devised the means above described to make such discovery of practical benefit.

I claim as new and desire to secure by Letters Patent—

1. Lining the interior surfaces of the cylinders of engines operated by steam or heated gas with glass, porcelain, enamel, or equivalent substance, in manner substantially as described, to produce the results specified.

2. The combination of the cylinder X with the cylinder N, or its equivalent.

3. The elongated piston A, in combination with the lining or protecting material *x x*.

4. The combination of the pipe *b* with the piston-rod or trunk, all substantially as and for the purposes herein set forth.

CHAS. E. EMERY.
